(57) **CLAIM**

The ornamental design for the stage light, as shown and described.

DESCRIPTION

FIG. 1 is a front and top perspective view of a stage light design showing my new design.

FIG. 2 is a rear and bottom perspective view of the stage light.

FIG. 3 is a front view of the stage light.

FIG. 4 is a rear view of the stage light.

FIG. 5 is a left side view of the stage light.

FIG. 6 is a right side view of the stage light.

FIG. 7 is a top view of the stage light; and,

FIG. 8 is a bottom view of the stage light.

Any shading and cross-hatching are not features of the design but are utilized to illustrate the surface contours of the stage light design in the drawings.
